UNITED STATES PATENT OFFICE.

RUDOLF R. KARICH, OF WOODHAVEN, NEW YORK, ASSIGNOR TO THE AMERICAN TAXIMETER COMPANY, OF NEW YORK, N. Y., A CORPORATION OF NEW YORK.

HUB-ODOMETER REGISTER DRIVE.

Application filed April 19, 1921. Serial No. 462,536.

To all whom it may concern:

Be it known that I, RUDOLF R. KARICH, a citizen of the United States, residing at Woodhaven, Long Island, in the county of 5 Queens and State of New York, have invented certain new and useful Improvements in Hub-Odometer Register Drives, of which the following is a specification.

This invention relates to hub odometers, 10 and more particularly to an improvement in the means for operating the counter or register thereof.

A primary object of the invention is to provide a simple and durable construction 15 that will reliably function under all conditions of use and which may be economically manufactured and easily and quickly assembled.

The invention also contemplates novel 20 means for insuring the positive transmission of motion from the moving vehicle wheel to the register or counter by providing adequate and efficiently distributed wear surfaces, thereby reducing to a minimum 25 the development of looseness or lost motion which would otherwise result. Owing to the relatively minute character of the driving connections due to limited space of installation, and the rapidity of operation 30 the arrangement and distribution of parts to reduce wear is important to the life of the instrument. Therefore, it is proposed to provide operating connections which have the wear surfaces distributed in such manner 35 as to avoid lost motion as a result of wear thereby materially adding to the life of the device and insuring its accuracy and reliability.

With the above and other objects in view, 40 which will more readily appear as the nature of the invention is better understood, the same consists in the novel construction, combination and arrangement of parts hereinafter more fully described, illustrated 45 and claimed.

A practical embodiment of the invention is shown in the accompanying drawings, in which—

Figure 1 is an enlarged front elevation 50 of a rotor of a hub odometer drive having the present improvements applied thereto.

Figure 2 is a horizontal sectional view taken on the line 2—2 of Figure 3.

Figure 3 is a transverse sectional view 55 taken on the line 3—3 of Figure 1.

Similar reference characters designate corresponding parts throughout the several figures of the drawings.

By reference to the accompanying drawings, it will be observed that the present invention includes in its organization, a suitable rotor element R, the same having the threaded portion 1 for fitting into a conventional odometer casing carried by the wheel hub and rotating therewith in the well known manner. Due to the limited space available within the hub odometer casing for installing the counter device and the operating mechanism therefor, the rotor is preferably recessed as at 2, and the central portion of said recess is provided with an opening 3 for receiving the stem 4 of a stator element. This stator element is designated generally as S and includes the base 5 which may be of the relatively flat and circular formation shown in Figure 1, and the stem 4 thereof extending to one side thereof is adapted to connect in the well known manner with the axle, or stationary axle part, to thereby hold the stator 80 S in a fixed position while the rotor R rotates with the wheel. This stator element constitutes a stationary support for the counter or register mechanism indicated by the posts P and dotted circles W representing the register disks.

The said rotor R is provided within the recess 2 with a circular driving cam 6 whose axis is eccentric to the axis of the rotor R. The circular periphery 7 of the cam 6 is 90 adapted and intended to fit within a corresponding opening in an oscillating actuating yoke 9. This yoke preferably has the offset body portion 10 adapted to carry a suitable pawl supporting shaft or pin 11 95 adapted to have a slidably engagement with the base 5 of the stator as will presently appear.

In connection with the oscillating actuating yoke 9, it is to be observed that the 100 same may be readily stamped or punched from a flat sheet of metal which is desirable from a manufacturing stand-point, and also by reason of the fact that the periphery of the cam 6 is circular and the opening 105 in the yoke 9 is also circular no special design of punch is necessary for forming this part of the driving connections. Furthermore, by reason of the interfitting of the circular cam 6 within the circular opening 8 110

of the yoke, the bearing surface between the cam and the yoke extends over the entire periphery of the cam and is thus distributed over a relatively large area thereby reducing wear between these two parts to a minimum.

The said pin 11 of the oscillating actuating yoke carries an operating pawl 12 and is guided in its movement in a suitable 10 slot 13 in the base 5 of the stator. Thus, the pin 11 is compelled to reciprocate in the slot while the body of the yoke oscillates under the influence of the rotating cam 6 and the pawl 12 is moved back and forth to perform 15 its working stroke. That is to say, this reciprocating movement of the pin 11 which carries the pawl 12 is utilized to operate a main ratchet wheel 14 journaled as at 15 upon the base 5 of the stator and carrying therewith one of the spur gears 16 and constituting a driving gear unit for operating the train of registering wheels W whose 20 positions on the aforesaid posts P are indicated by dotted lines in Figure 1.

To hold the main operating pawl 12 always in operative engagement with the periphery of the ratchet wheel 14, a suitable spring 17 may be used as shown in Figure 1, and for the purpose of preventing retrograde movement of the said ratchet wheel 14, the opposite end 18 of the said spring 17 may be arranged to press the detent end of a keeper pawl 19 also into engagement with the teeth of the ratchet wheel 14. This 35 keeper pawl 19 is preferably mounted in any suitable manner as by the screw 20, concentric with the axis of the base 5 of the stator, and therefore it serves no other function than to check or prevent backward 40 movement of the ratchet wheel 14 with which it is always engaged.

When the parts are assembled as shown in the drawings, and as above described, the rotation of the rotor R will obviously cause 45 the cam 6 to rotate and thus oscillate the yoke 9. And, as previously explained, the oscillating movement of the yoke under the influence of the cam 6 will be turned into reciprocating motion at the end of the offset 50 portion 10 of the yoke, due to the pin 11 carried by the said offset being guided in the slot 13 of the base. As the pawl 12 is carried by the pin 11, it is adapted to reciprocate in the direction of the arrow shown in 55 Figure 1, and upon moving to the right in that figure, said pawl will trail over the teeth of the ratchet but when moving in the opposite direction, that is to the left, it will cause

the ratchet wheel 14 to be rotated through a part of its cycle. Obviously the repetition 60 of this action will cause the ratchet wheel 14 to rotate in accordance with the speed at which the vehicle is being driven, and as the ratchet wheel 12 carries a gear for transmitting motion to the first of the train 65 of register wheels W, the latter will be operated in the usual manner to give the desired indications through the window of the hub odometer casing.

Without further description, it is thought 70 that the features and advantages of the present invention will be readily understood, and it will of course be apparent that changes in the form, proportion and minor details of construction may be resorted to 75 without departing from the spirit of the invention or scope of the appended claims.

I claim:

1. A driving mechanism for hub odometer registers including a rotor having a driving 80 cam thereon, a stator having a slot, a register driving gear mounted on the stator, and a yoke having guiding engagement in said slot and reciprocated by the cam on the rotor, and a pawl carried by said yoke for 85 engaging with the register driving gear.

2. A driving mechanism for hub odometer registers including a rotor, a driving cam on the rotor, a stator having a slot, a register driving gear on the stator and adjacent the 90 slot, a yoke engaging said cam and reciprocated thereby, a pin carried by the yoke and projecting through said slot and having a guiding engagement therein, and a spring 95 pressed pawl carried by the pin and adapted to engage the driving gear.

3. A driving mechanism for hub odometer registers including a rotor, a driving cam arranged centrally thereon, a stator spaced from the face of the rotor, and having a slot 100 opening at the edge thereof, a register driving gear on the stator adjacent the slot, a yoke member arranged in the space between the stator and the rotor as above described, and engaging with said cam, a pawl supporting member carried by the yoke and having a guiding engagement in said slot of the stator, and a spring pressed pawl on said member and adapted to engage with the driving gear. 110

In testimony whereof I hereunto affix my signature in the presence of two witnesses.

RUDOLF R. KARICH.
